Thomas Barry (Assignor of J. H. Ranson) New York.
Letters Patent (Design No. 104) dated 5th January 1847.

The schedules referred to in these Letters Patent and making
part of the same.

To all whom it may concern; Be it known that I, Thomas Barry

of New York, in the County of New York, and State of New York, have invented a new and useful ornamental design for a box stove; and I do hereby declare that the accompanying drawings, making part of this specification, are full and accurate representations of my said design; in which Fig. 1, represents a perspective view of one of my stoves; - Fig. 2, a side plate upon a larger scale, to shew the detail of ornament; - Fig. 3, an end plate, and Fig. 4, the hearth. To save labor in drawing, the ornaments upon but one half of the plate Fig. 2, have been delineated, the remaining portion being similar to, and symmetrical with those represented. Fig. 5, represents a portion of the border $\frac{1}{2}$ of the top plate (See Fig. 1.) The sides and ends are ornamented with a series of recessed arches - all the figures being in the style of Louis XIV, and though not easily described in words, are fully represented in the drawings.

What I claim as my invention, and desire to secure by letters patent is, the combination and arrangement of ornamental figures shown in the accompanying drawings, forming an ornamental design for a box stove.
